(57) **CLAIM**

The ornamental design for an extrusion for frames, as shown and described.

DESCRIPTION

FIG. 1 is a perspective view of an extrusion for frames showing my new design;

FIG. 2 is a front elevation view thereof;

FIG. 3 is a rear elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The extrusion for frames is shown with a symbolic break in its length. The appearance of any portion of the extrusion for frames between the break lines forms no part of the claimed design.
